Greensboro, N.C., a corporation of North Carolina

Original application April 9, 1954, Serial No. 422,173.
Divided and this application January 18, 1955, Serial No. 485,575

14 Claims. (Cl. 343—803)

The present invention concerns improvements in an antenna structure, and particularly in antennas of the type disclosed and claimed in copending application, Serial No. 418,553, filed March 25, 1954, in the name of Yuen Tze Lo and entitled "Wide Band Antenna." The present application is a division of my co-pending application Ser. No. 422,173 of the same title, filed April 9, 1954.

In the mounting of television antennas, generally upon roof tops, installers must work in precarious and dangerous positions. It is therefore important to provide antennas which can readily be assembled and handled during erection, with a minimum of tools and manual operations, so as to minimize the dangers of such installations.

In addition, from the view point of the manufacturer, it is important that the various component parts be simply fabricated and assembled at the factory, to provide an antenna which can be compactly and simply packaged and yet quickly unpacked and assembled at the installation spot, while still providing efficient electrical operation and rigidity in the mounted condition.

These and other advantages and objects of the present invention will be more readily understood from consideration of the following description taken in conjunction with the appended drawings, in which

Fig. 1 is a perspective assembly view of one form of the present invention.

Fig. 2 is a fragmentary front view of the structure of Fig. 1.

Fig. 3 is a fragmentary bottom view of the structure of Figs. 1 and 2, partly in section, viewed along line 17—17 of Fig. 2.

Fig. 4 is a fragmentary top view of the structure of Figs. 1—3, viewed along line 19—19 of Fig. 2.

Fig. 5 is a fragmentary elevation view, partly in section, of a dipole clamping means, viewed along line 20—20 of Fig. 2.

Fig. 6 is a fragmentary elevation view, partly in section, of another dipole clamping means, viewed along line 21—21 of Fig. 2.

Fig. 7 is a perspective view of a two-bay arrangement of the structure of Fig. 1.

The present invention is illustrated particularly as applied to a "tri-pole" or triple dipole arrangement for wide-band television reception, whose principles are described in the aforementioned Lo patent application, although in its broader aspects the present invention is not limited thereto. As disclosed in said Lo application, the tri-pole antenna has one long or low-band dipole above and below which are respective ones of a pair of short or high-band dipoles, interconnected by a transmission line harness having three transmission line sections coupled to a pair of common terminals, the antenna having also a vertical reflector screen spaced from the dipole array. Fig. 1 is a perspective view of an embodiment of the Lo "tri-pole" antenna incorporating structural features according to the present invention.

As shown in Fig. 1, a long (low-band) folded dipole

2

51 is mounted substantially in a horizontal plane above and below which are the short (high-band) folded dipoles 52 and 53, equally spaced therefrom, and also in respective horizontal planes. The long dipole 51 is spaced closely and parallel to the short dipoles 52, 53, their electrical characteristics and interrelationship being described in said Lo application.

All of the dipoles 51, 52, 53 are mounted on a vertical post 91 which in turn is secured to a horizontal cross arm 54, which is supported from a vertical mast 55, usually mounted on the house or building structure. The cross arm 54 also supports the reflector screen 56, shown in this instance as a plurality of parallel horizontal rods 57 with a pair of joined vertical rods 58. This structure is described more in detail below. A transmission line harness 46 interconnects the dipoles 51, 52, 53 to a terminal block from which the down-lead transmission line extends to the receiver.

The structural features of this antenna, which provide advantages in fabrication, in structural strength and stability, and in ease of assembly, are shown in Figs. 2—7. As will be seen, the antenna structure as a whole is made collapsible and foldable, so that it may be readily packed for shipment and then, in a simple manner, erected with a minimum of effort and the use of a minimum number of tools. The long dipole 51 is made of conductive tubing, such as aluminum tubing, and as seen most clearly in Fig. 3, may be formed of a single long rod 71 having its ends bent and flattened as at 72, in association with a pair of shorter rods 73, each having a similar bent and flattened end 74 secured to a respective end 72 as by riveting at 75. The other ends of the shorter rods 73 are flattened as at 76, and are riveted or otherwise suitably fixed to an insulating block 77, such as of Bakelite, Mica, carton or the like. The coupling harness indicated generally at 46 has three transmission line section branches, one branch 79 having its respective terminals joined to the flattened ends 76 of the rods 73, as by the same rivets which secure rods 73 to block 77. The other terminals of this harness branch 79 are riveted or otherwise secured to the terminals 81 of a terminal block 82 to which are also joined the other harness branches 83 and 84, leading to the smaller dipoles 52 and 53.

The smaller dipoles 52 and 53 are formed similarly to the long dipole 51, each having a long uninterrupted side 86 and an interrupted side parallel thereto, having arms 87 with flattened ends 88 joined to a respective insulating block 89 and 90. Where desired, each of these folded dipoles 51, 52 and 53, can be made of a single piece of tubing bent into a flat elongated loop with one uninterrupted side and the other side interrupted at its center to form two adjacent ends mounted on terminal blocks such as 77, 89 and 90, as shown for small dipole 52 in Fig. 4, or they may be made of separate rods joined at their ends as described relative to dipole 51 and shown in Fig. 3.

For the purpose of rigidly mounting the dipole assembly from the cross arm 54, a vertical supporting post 91 is provided which has a bayonet socket or other suitable clamp 92 at its center extending perpendicularly thereto for the purpose of receiving the end of the cross beam 54. As shown at Fig. 5, the socket 92 may be secured by rivets, bolts, welding or the like to the supporting post 91, as at 93, and may have the cross arm 54 secured thereto as by a screw or projections 94. For assembly, with screw 94 loosened, cross arm 54 is inserted into the socket 92 with the screw shaft registering with slots 100 of socket 92. The slots 100 have right-angled branches into which screws 94 seat. Then a wing nut 94a may be tightened on screw 94 to make a rigid structure. It will be understood that while this is a simple and convenient arrangement for joining the cross beam 54

to the supporting arm 91, other equivalent means may be utilized.

For purposes of ease of packing and shipment, and of assembly on the job, each of the dipoles 51, 52 and 53 is pivotally joined to the supporting post 91 so that this sub-assembly can be folded with post 91 essentially parallel to all three dipoles superposed on one another, and the assembly is adapted upon unfolding to be locked or clamped to the post 91 perpendicularly thereto. For this purpose, each of the short dipoles 52 and 53 has a clip 95 secured thereto as by a long rivet 96 passing diametrically through the supporting post 91 and through the tubing 86 forming the long side of the dipole, at its center. The clip 95 is formed of two sections 95a and 95b, each having a groove formed therein to receive the dipole tubing 86. Clip portion 95b is formed with an elongated flat portion 97, having a pointed detent 98 extending at right angles therefrom. When the short dipole 52 or 53 is rotated about the pivot axis formed by rivet 96, to a position of perpendicularity to the supporting post 91, the detent 98 slips into a hole 99 formed in the supporting post 91, and serves to retain the dipole in this perpendicular relationship to supporting post 91. It will be understood that the clip portion 97 has sufficient resilience to permit the detent 98 to spring into and be retained in the hole 99 for locking the dipole in place. Also held by the rivet 96 is a rigid wire support 101 having an eyelet at its opposite end which is riveted as at 102 to the center of the insulating block 89 which spaces the terminal ends 88 of the short dipoles 52 and 53. This wire 101 serves to maintain the end terminals 88 of the short dipoles 52, 53 in rigid relationship to the remaining structure.

As shown in Figs. 2 and 5, the long dipole 51 is similarly pivotally secured to the supporting post 91 by a long rivet 103 passing through post 91 and the tubing section 71 of the long dipole 51. A clip 105, having portions 105a and 105b, is also secured to the dipole tubing 71 by the rivet 103. Clip portions 105a and 105b have grooves formed therein for receiving the dipole tubing 71. Clip portion 105b is extended in a flat plate 106 shown in Fig. 2, having a slot 107 for receiving a screw 108 passing through the supporting part 91 and having a wing nut or similar type clamping means 109 at the other end. In this way, the long dipole 51 may be swung at right angles to the supporting post 91 to a position where the screw 108 engages with the slot 107 of the clip portion 106. Tightening nut 109 then clamps the long dipole 51 in proper position rigidly.

A rigid wire support 111 is also secured by rivet 103 to tubing 71 and extends to the insulating block 77 joining the ends 76 of the long dipole 51 to maintain the dipole portions in proper electrical and mechanical relationship.

The ends of the branches 83 and 84 of the coupling harness are riveted respectively to the ends of the short dipoles 52, 53 by the same rivets which connect these dipole ends to their insulating blocks 89 and 90, and the other ends of these harness branches 83 and 84 are joined together to the terminals 81 of terminal block 82.

It will thus be seen that the collapsed assembly of dipoles 51, 52 and 53 and the supporting arm 91 is easily unfolded into operative position merely by rotating each of the short dipoles 90° until its detent 98 snaps into hole 99. Similarly, the long dipole is rotated 90° and clamped in position by the screw 108 and wing nut 109. The cross beam 54 is then inserted in the bayonet type socket 92 and secured by the screws 94. The terminal block 82 may then be secured to cross beam 54 by a screw passing through holes 80 and 121 in the block 82 and beam 54, respectively.

The cross beam 54 is preferably pivotally connected to the screen 56, as shown in Fig. 1, by being pivotally secured to the center enlarged horizontal supporting bar 113 of the screen 56. Suitable clamping means, shown generally at 110, are provided so that the cross arm 54

may be locked into position perpendicularly to the plane of the reflector screen 56, as by way of a suitable wing nut and slot arrangement of the general character of plate 106 and screw 108 of Figs. 2 and 5. The screen 56 is also made collapsible by having all of its horizontal rods 57 pivotally secured to the vertical rods 58. At the points 114 at which the vertical rods 58 cross the center horizontal rod 113, locking means may be provided to maintain the screen locked in its proper open position. For example, a vertical groove may be formed in the outer surface near each end of the center rod 113 to accommodate one of the vertical rods 58 and the pivot at points 114 may be formed by wing nut and screw arrangements which rigidly clamp the vertical rods 58 to the horizontal rod 113 in only one position where the rods 58 seat in the said grooves so that these rods 58 and 113 are perpendicular to one another. The entire screen is then locked into proper relationship by this arrangement. The mast 55 may be clamped to the cross beam 54 by a conventional type of U-clamp 115, as shown in Fig. 1.

As an important aspect of the invention, it will be noted that each of the dipoles is conductively connected to the mast, at the center of the long uninterrupted conductor thereof, opposite its terminal block. At this point, because of symmetry considerations, the antenna is at fixed potential and is hence grounded, serving as a protection against lightning injury to the receiver.

In instances where it is important to provide a higher gain, the invention may be utilized in a stacked array having multiple bays, one above the other. Fig. 7 illustrates a two-bay arrangement formed by two units of the type described above. Each of the dipole assemblies 134 is described above, each being secured to a respective cross beam 54, which in turn is clamped in the manner already described to its respective reflector screen 56. For the purpose of joining the two reflector screens into a single screen, the ends of vertical rods 58 are flattened and apertured, so that the two aligned vertical rods 58 can be bolted together as at 141. Aligned ridges and grooves may be formed in these ends to maintain their alignment seated on one another.

The mast 55 is then clamped at 115, to each cross beam 54. A further coupling harness is provided, having a terminal block 136 from which respective transmission line branches 137 of equal length proceed to the respective terminal blocks 82 of the individual bays 134, secured to the cross beams 54 as described above. A further terminal block 138 is mounted on mast 55 between the cross beams 54, and a line section 139 extends from block 138 to block 136. The line sections 137 and 139 are preferably formed by rigid rods, the sections 137 serving properly to space the two dipole assemblies, and section 139 holding sections 137 rigidly in place. The down lead transmission line 23 is then secured to the terminals on block 138.

In a similar manner a four-bay arrangement may be provided, by connecting down lead 23 to the center of a line section connecting two terminal blocks 138.

It will thus be seen that the present invention provides a simple and efficient wide-band antenna arrangement, easy to fabricate and assemble, and effective over the entire VHF range of broadcast television.

It is to be understood that the above description is illustrative only, since equivalent structural features may be utilized where desired, the present invention being defined by the appended claims.

What is claimed is:

1. An antenna comprising a dipole of the folded type formed by a narrow elongated planar loop of rigid conductive material having a long uninterrupted side and a parallel interrupted side having a gap substantially at the center thereof, said sides being joined at their ends, an insulating terminal block secured to the ends of said interrupted side on either side of said gap, a conductive supporting post for said dipole, means pivotally securing

said uninterrupted side to said supporting post at the center of said latter side and in conductive relation thereto, with the axis of said pivot in the plane of said loop, and a rigid strut extending from the center of said terminal block to the center of said uninterrupted side for rigidly maintaining said two dipole sides in substantially parallel relationship.

2. An antenna as in claim 1, further comprising means for clamping said post perpendicular to the plane of said dipole loop.

3. An antenna as in claim 2, wherein said clamping means comprises a bolt passing through said post and spaced from said pivot axis, and a plate fixed to said dipole and having a slot engaging said bolt when said loop plane is perpendicular to said post.

4. An antenna as in claim 1, further including a pair of shorter dipoles, each of the folded type formed by a narrow elongated planar loop of rigid conductive material having a long uninterrupted side and a parallel interrupted side having a gap substantially at the center thereof, said sides being joined at their ends, means pivotally mounting each of said uninterrupted sides on said post on respectively opposite sides of said first dipole and with the pivot axis of each of said short dipoles in the plane of its loop, an insulating terminal block connected to the ends of said interrupted sides of each of said short dipoles and extending across the gap thereof, and a pair of further rigid struts each connected at one end to one of said latter pivotal mounting means and at the other end to a respective block for maintaining the sides of said short dipoles in spaced parallel relation, the uninterrupted conductors of each of said short and long dipoles being conductively connected to said post at the centers thereof.

5. An antenna as in claim 4, further comprising a cross beam secured to said post perpendicularly thereto, and a mast secured to said cross beam perpendicularly thereto for mounting said three dipoles in a vertical plane with each dipole in a respective horizontal plane.

6. An antenna as in claim 5, further including a screen reflector mounted on said cross beam at the end opposite said post and parallel to the plane of said dipole arrangement.

7. A collapsible antenna arrangement comprising a post adapted to be supported in a vertical position and a plurality of folded dipoles pivotally secured to said post at spaced positions therealong, each of said dipoles being formed as an elongated planar loop of conductive material having an uninterrupted side and a side parallel thereto interrupted by a gap at its center, and an insulating block straddling said gap and connected to the adjacent ends of said interrupted side, each of said dipoles being pivotally and conductively secured to said post at the center of its uninterrupted side.

8. An antenna as in claim 6, further including clamping means for maintaining said dipoles in perpendicular relationship to said post.

9. In an antenna arrangement, a supporting post, an

5

antenna element having a conductive rod as a portion thereof, a pin extending diametrically through said post and said rod for pivotally securing them together, a resilient plate secured to said conductive rod for joint rotation therewith, said plate having a detent tip bent at right angles to said plate, said post having a recess adapted in one position of said rod to receive said detent, said plate being resilient to permit said detent to enter into said recess and for retaining said detent in said recess to clamp said antenna in a predetermined position with respect to said post.

10. An antenna arrangement as in claim 9, wherein said plate has a grooved portion conforming to and in contact with said rod, said pin constituting a rivet passing also through said plate and securing said plate to said rod.

11. A collapsible antenna structure comprising a cross beam adapted to be secured to a vertical mast, a post removably secured to said cross beam at one end and perpendicularly thereof to be mounted in a vertical position, three dipoles pivotally secured to said post at spaced positions therealong, and means for clamping said dipoles to said post perpendicularly thereof to form a vertically arranged horizontal dipole array.

12. A collapsible antenna structure as in claim 11 wherein at least one of said clamping means comprises a resilient arm fastened to and extending substantially at right angles to the axis of a dipole, a recess in said post, and a projection on said arm extending toward said post and adapted to snap into engagement with said recess when said dipole is turned to a right angle with respect to said post.

13. An antenna as claimed in claim 8 wherein at least one of said clamping means comprises a resilient arm fastened to and extending substantially at right angles to the axis of a dipole, a recess in said post, and a projection on said arm extending toward said post and adapted to snap into engagement with said recess when said dipole is turned to a right angle with respect to said post.

14. In an antenna arrangement a supporting post, an antenna element having a conductive rod as a portion thereof, means for pivotally attaching said conductive rod to said post, a resilient arm fastened to and extending substantially at right angles to the axis of rotation of said dipole, a recess in said post and a projection on said arm extending toward said post and adapted to snap into engagement with said recess when said dipole is turned to a predetermined angle with respect to said post.
